UNITED STATES PATENT OFFICE.

FRANK W. MERRICK, OF BOSTON, MASSACHUSETTS.

LOCK-STITCH SEWING-MACHINE.

No. 872,074.

Specification of Letters Patent.

Patented Nov. 26, 1907.

Application filed June 17, 1904. Serial No. 212,930.

To all whom it may concern:

Be it known that I, FRANK W. MERRICK, a citizen of the United States, residing at Boston, in the county of Suffolk, State of Massachusetts, have invented a certain new and useful Improvement in Lock-Stitch Sewing-Machines, of which the following is a specification, reference being had therein to the accompanying drawings.

10 In the drawings,—Figure 1 shows in front elevation a portion of a sewing machine with an embodiment of the invention applied thereto. Fig. 2 shows the parts of Fig. 1 in plan, with the work-support, awl-bar, and awl omitted, and a small portion of the shuttle in section. Fig. 3 shows the part of Fig. 1 in elevation looking from the left hand side in such figure. Fig. 4 is a partly sectional detail of the shuttle on a somewhat larger 20 scale, showing the pressure-member carried thereby, and the means of adjusting the said pressure-member. Fig. 5 is a sectional view showing the employment of a supplemental disk as the inner pressure-member. Fig. 6 is 25 a view illustrating the application of the invention to a curved-needle lock-stitch sewing machine.

Having reference to the drawings,—a portion of a post or standard forming part of the 30 frame-work of a sewing machine is represented at 1, Figs. 1 and 2, and at 2 is represented a work-rest or work-support upon the upper end of the said post or standard 1. 3, in Fig. 1, is an awl working from above the said 35 work-rest or work-support, and 31 is the awl-bar carrying the said awl. Only a portion of the awl-bar is shown.

4 is an ordinary hooked needle working from below the work-rest or work-support, 40 and 41 is the needle-bar carrying the said needle, only a portion of the needle-bar being shown. The awl-bar and needle-bar in practice respectively have connected therewith suitable means for reciprocating the same, 45 and respectively are mounted in guides (not shown) as usual.

5 is a rotary loop-taker having the working position thereof below the work-rest or work-support. In the present embodiment of the 50 invention, the said loop-taker is in the form of a shuttle. The said shuttle is essentially cup-shaped, it being formed with a large chamber or cavity which is concentric, or substantially so, with the axis of rotation of the shuttle, and with a raised annular rim 55 surrounding the said chamber or cavity.

51 is a thread-container, herein a bobbin which is mounted concentrically, or substantially so, with the said axis of rotation of the loop-taker. Herein it is contained within 60 the chamber or cavity of the shuttle.

52 is a shuttle-driver, and 53 is an upright shaft having the said shuttle-driver attached thereto, the said shaft being mounted in bearings in the post or standard 1. In practice, the said shaft 53 has connected therewith suitable means for rotating the same, not necessary to be shown. The shuttle 5 is mounted in a shuttle-race comprising opposite side-pieces 6, 6, and a removable section 70 or slide 61 between the said side-pieces, the edges of the portions 6, 6, 61, of the shuttle-race entering a circumferential groove 54 which is formed in the exterior of the shuttle, and the removability of the section 61 providing for the insertion and withdrawal of 75 the shuttle.

The shuttle-point is designated 43.

As so far referred to, the parts work in usual and well-known manner, and during 80 operation the shuttle-thread leads from the bobbin 51 upon which it is wound, over the upper rim of the shuttle, to the stitch-making point in the machine, where it is incorporated in the stitches of the seam which is 85 being produced in the stock being sewed.

The principles which are embodied in my invention are as follows:—After a loop of needle-thread has been engaged by the shuttle-point and passed around the shuttle by 90 the rotation of the latter, and been cast off from the shuttle, and as the tightening of the stitch advances to completion, a surface with which the shuttle is provided passes beneath and outside the portion of shuttle-thread extending over the rim of the shuttle from the interior of the latter toward the stitch-forming point. The said exterior surface presses the said portion of the shuttle-thread radially inward toward the axis of rotation of 100 the shuttle, against an inner surface which is concentric with the shuttle-axis, and thereby in passing temporarily clamps the shuttle-thread between the seam and the source of supply within the shuttle. The clamping is 105 timed so as to impart the requisite tension to the shuttle-thread as the tightening of the stitch occurs, and to lock the shuttle-thread to withstand the final pull on the needle-thread in setting the stitch. Usually I 110 shape or construct the said exterior surface to precede the locking of the shuttle-thread

for the setting of the stitch by an additional, less positive, compression of such thread, whereby to hold the latter just sufficiently to retard the advance thereof in response to that 5 portion of the tightening of the stitch which precedes the final setting. Ordinarily, the shuttle-thread locking action will not be sufficiently pronounced in practice to hold such thread up to the breaking point of the latter. 10 The exterior surface is made adjustable, to accommodate different sizes of shuttle-thread, as well as to enable the same to be set to act with the required accuracy, in compressing the thread against the coacting 15 surface to the required degree. When a bobbin is employed within the shuttle, the concentric inner clamping surface is, according to the preferred embodiment of my invention, constituted by a disk connected 20 with or forming part of the shuttle-bobbin, as, for instance, by one of the bobbin-heads or disks. When this is the case, the clamping of the shuttle-thread between the outer clamping-surface and the said disk serves, by 25 arresting the rotation of the bobbin and locking the same from turning, to prevent overrunning thereof.

In the illustrated embodiments of the invention the outer thread-compressing surface 30 face is designated 7. It forms part of an arm 71, the latter constituting portion of a lever which is mounted by vertical pivot 72 on the upper portion of the rim of the shuttle. The inner surface with which the surface 35 face 7 co-operates, concentric or co-axial with the shuttle, is constituted by the peripheral rim of the upper head or disk of the bobbin 51 in Figs. 1, 2, 3 and 4. The surface 7 occupies a position, exterior to the said rim, in 40 which it nearly or just touches the latter. It is so located upon the shuttle that, as already indicated, after the loop of needle-thread which has been engaged by the shuttle point has been passed around the shuttle by 45 the rotation of the latter and discharged from the shuttle-point, and as the needle-thread is drawn up in tightening the stitch it, the said surface 7, shall arrive in the rotary motion of the shuttle in position to act 50 against the portion of shuttle-thread extending from the bobbin to the seam.

In order that just before the shuttle-thread is firmly pinched or locked between the surface 7 and the bobbin, the said thread 55 may be held for a brief period sufficiently to retard the advance thereof during that portion of the tightening of the stitch which precedes the final setting of the latter, the arm 71 is provided with a surface 73 approaching the peripheral edge of the head of the bobbin but less closely than the surface 7. This surface 73 is presented first to the shuttle-thread in the rotation of the shuttle and acts to partially compress the shuttle-

thread against the periphery of the bobbin-head or disk so as to retard the rendering of such thread without actually stopping the same. The surface 7, next coming into action, then effects the temporary locking of the shuttle-thread, as already explained. 70 For rendering the surfaces 7 and 73 adjustable in the direction toward and from the edge of the head of the bobbin, the lever is provided with an adjusting screw 74, which latter is fitted to a threaded hole that is 75 tapped in the arm 75 of the said lever, and takes by its inner end against the surface of the wall of the recess 44, in the upper portion of the rim of the shuttle, in which the lever is received. 80

The invention is equally applicable either to straight needle machines as in Figs. 1, 2 and 3 of the drawings, or to curved needle machines as in Fig. 6. In the latter figure, a work-support is indicated at 111, a curved awl at 113, an oscillating awl-carrier at 131, a curved needle at 114, and an oscillating needle-carrier at 141. At 115 is a rotary shuttle co-operating with the said curved needle in the production of stitches, at 159 90 the shuttle point, at 152 the shuttle-driver, at 153 the rotary shaft on which the said shuttle-driver is mounted, and at 156 the shuttle-race. The outer disk or head of the bobbin, and the shuttle-thread locking lever, 95 have the same reference characters applied in connection therewith as in the case of Figs. 1 to 3. An elastic or yielding arm, 119, is attached by means of a screw 120 to the portion 121 of the machine-framing. The 100 free extremity of the said arm projects in front of the shuttle and makes contact with the outer side of the disk or head 51 of the bobbin. The said arm serves to retain the bobbin in place within the shuttle. 105

I contemplate in some cases employing a supplemental disk as the inner clamping or pressure-member for the shuttle-thread, and supporting the same in a working position adjacent one of the heads of the bobbin, to 110 co-act with the outer pressure-member. One construction embodying such a supplemental disk is represented in Fig. 5, in which the said disk is designated 8. The supplemental disk is supported conveniently in working 115 position, as, for instance, by providing the same with a central spindle 81 extending downward therefrom and entering the bore or interior of the tubular central post 511 of the shuttle. It is supported vertically by an 120 annular shoulder thereon at the top of the said post, which rests upon the upper end of the post. The peripheral margin of the disk is located in close proximity to the upper 125 margin of the rim of the shuttle, in the plane of the working portion of the outer pressure-member. The disk 8 may be capable of turning loosely or independently with rela-

tion to the shuttle, in which case its spindle 81 will fit loosely within the tubular post of the shuttle. The disk, however, may be fixedly mounted in a manner preventing it 5 from rotating independently with relation to the shuttle, as, for example, by proportioning the spindle 81 to fit tightly within the tubular post of the shuttle and engage frictionally therewith so as to prevent the rotation of the said spindle within the said post. For the purpose of holding the disk 8 in its working position, a spring 9 is shown in Fig. 5 attached to the under surface of the top plate of the work-support 2. The said 10 spring is a leaf-spring, and is connected with the work-support at one end thereof, the free portion of the spring being bent or curved downward to bear against the upper side of the disk, and an adjusting screw 91 being applied to a threaded hole that is tapped in the work-support, the end of the said adjusting screw making contact with the spring. By means of the adjusting screw the bent or curved portion of the spring may be caused 15 to bear properly against the disk, and the degree of its pressure may be regulated conveniently.

I am aware of the application of Henry H. Cummings, Serial No. 212,929, filed June 17, 30 1904, in the same interests as this application; said Cummings application relating to an invention similar, generically, to the invention of the present case; but as I am the inventor of the generic idea common to the 35 two cases, and as the Cummings construction is a later development of my generic invention, it is the desire of the parties in interest that the broader or more generic claims relating to this invention be granted 40 to me without interference with the said Cummings case in which the claims have been limited so as not to overlap the claims of this application.

I claim as my invention:—

45 1. In a lock-stitch sewing machine, in combination, the rotary shuttle, an inner pressure-member for the shuttle-thread, and an outer pressure-member mounted upon the shuttle and carried by the rotation of the latter past the shuttle-thread at the outer side thereof, the said outer member acting as it passes the shuttle-thread to press the same radially inward against the said inner member and thereby clamp the shuttle-thread as 50 the stitch is being set.

2. In a lock-stitch sewing machine, in combination, the rotary shuttle, an inner pressure-member for the shuttle-thread, an outer pressure-member mounted upon the shuttle 55 and carried by the rotation of the latter past the shuttle-thread at the outer side thereof, the said outer member acting as it passes the shuttle-thread to press the same radially inward against the said inner member and

thereby clamp the shuttle-thread as the 65 stitch is being set, and adjusting means to vary the relation of the pressure-members to each other.

3. In a lock-stitch sewing machine, in combination, the rotary shuttle, the inner pressure-member, between which and the rim of the shuttle the shuttle-thread passes from the source of supply within the shuttle to the stitch-forming point, and the outer pressure-member mounted upon the shuttle, acting 70 exteriorly against the shuttle-thread as it passes the latter to pinch the same against the said inner member.

4. In a lock-stitch sewing machine, in combination, the rotary shuttle, the inner pressure-member, between which and the rim of the shuttle the shuttle-thread passes from the source of supply within the shuttle to the stitch-forming point, the outer pressure-member mounted upon the shuttle, acting 75 exteriorly against the shuttle-thread as it passes the latter to pinch the same against the said inner member, and adjusting means to vary the relation of the pressure-members to each other.

5. In a lock-stitch sewing machine, in combination, the rotary shuttle, a disk mounted co-axially with the said shuttle, and the outer pressure-member mounted upon the shuttle and carried by the rotation of the 95 shuttle past the shuttle-thread, outside the latter, the said member acting as it passes the shuttle-thread to press the same radially inward against a surface of said disk and thereby pinch the shuttle-thread as the stitch 100 is being set.

6. In a lock-stitch sewing machine, in combination, the rotary shuttle, a central bobbin, and the pressure-member, mounted upon the shuttle, and carried by the rotation of the 105 shuttle past the shuttle-thread, outside the latter, the said member acting as it passes the shuttle-thread to press the same radially inward against the peripheral rim of a head of the bobbin and thereby pinch the shuttle- 110 thread to lock the latter as the stitch is being set.

7. In a lock-stitch sewing machine, in combination, the rotary shuttle, a disk mounted co-axially with the said shuttle, the outer 115 pressure-member, mounted upon the shuttle, carried by the rotation of the shuttle past the shuttle-thread, outside the latter, and acting as it passes the shuttle-thread to press the same radially inward against a surface of said disk and thereby pinch the shuttle-thread as the stitch is being set, and means to adjust 120 the relation of the said member to the said disk.

8. In a lock-stitch sewing machine, in combination, the rotary shuttle, a central bobbin, the pressure-member mounted upon the shuttle and carried by the rotation of the 125

shuttle past the shuttle-thread, outside the latter, the said member acting as it passes the shuttle-thread to press the same radially inward against the peripheral rim of a head 5 of the bobbin and thereby pinch the shuttle-thread as the stitch is being set, and means to adjust the relation of the pressure-member to the said rim.

9. In a lock-stitch sewing-machine, a rotating loop-taker having in connection therewith a source of supply for the locking thread, and provided with thread-compressing means operated by the rotation of the said loop-taker to first yieldingly hold said 10 thread for tension prior to the final tightening of the stitch and then lock the thread for the said final tightening.

10. In a lock-stitch sewing-machine, in combination, a thread-container, and a loop-taker, rotating around said thread-container, and provided with thread-compressing means operated by the rotation of the loop-taker to intermittently compress the locking 20 thread.

25 11. In a lock-stitch sewing-machine, in combination, a thread-container, and a rotating loop-taker which carries the loop of needle-thread around the said thread-container, the said loop-taker containing within 30 itself intermittently-acting locking-means for the thread from the said thread-container.

12. In a lock-stitch sewing-machine, in combination, a thread-container, and a rotating 35 loop-taker which carries the loop of needle-thread around the said thread-container, the said loop-taker containing within itself means operated by the rotation of the loop-taker to intermittently compress the 40 locking thread.

13. In a lock-stitch sewing-machine, in combination, a thread-container, a loop-taker which carries the loop of needle-thread around the said thread-container, the said 45 loop-taker containing within itself intermittently-operating radially-acting locking thread compression means.

14. In a lock-stitch sewing-machine, in combination, a thread-container, and a

loop-taker provided with thread-locking 50 means caused by the rotation of the loop-taker to clamp the locking-thread at a point between the thread-container and the stitch-forming point in the machine at the time of the tightening of the stitch. 55

15. In a lock-stitch sewing-machine, in combination, a thread-container, a loop-taker rotating around said thread-container and containing within itself means caused by the rotation of the loop-taker to intermittently compress the locking-thread at a point between the thread-container and the stitch-forming point in the machine at the time of the tightening of the stitch. 60

16. In a lock-stitch sewing-machine, in combination, a thread-container, a loop-taker rotating around the said thread-container and provided with radially-acting thread compression means caused by the rotation of the loop-taker to intermittently 70 operate upon the locking thread at a point between the thread-container and the stitch-forming point in the machine at the time of the tightening of the stitch. 75

17. In a lock-stitch sewing-machine, in combination, a thread-container from which the locking thread extends directly to the stitch-forming point in the machine, and a loop-taker rotating around the said thread-container, and provided with radially-acting 80 thread-compression means caused by the rotation of the loop-taker to intermittently compress the said thread at a point intermediate the thread-container and the said stitch-forming point. 85

18. In a lock stitch sewing machine, in combination, a rotating loop-taker, an adjacent disk, and a rotatable intermittent clamp acting to intermittently compress the locking thread against the edge of the said 90 disk as the said thread issues from a central source of supply past the said disk.

In testimony whereof I affix my signature in presence of two witnesses.

FRANK W. MERRICK.
